Primary Examiner — Jeffrey D Asch*Assistant Examiner* — Rebekah A Caruso(74) Attorney, Agent, or Firm — Banner & Witcoff, Ltd.(57) CLAIM

The ornamental design for a shoe upper, as shown and described.

DESCRIPTION

FIG. 1 is a front perspective view of a shoe upper showing my new design;

FIG. 2 is a side view thereof;

FIG. 3 is a top view thereof; and,

FIG. 4 is a rear perspective view thereof.

The broken lines within the shaded area represent features that form no part of the claimed design. The remaining broken lines immediately adjacent to the shaded area define the bounds of the claimed design, and form no part thereof. The further remaining broken lines showing the remainder of the shoe are for environmental purposes only, and form no part of the claimed design.
